SAMUEL W. RUSHMORE, OF PLAINFIELD, NEW JERSEY.

COOLING SYSTEM.

1,378,724

Specification of Letters Patent. Patented May 17, 1921.

Continuation of application Serial No. 428,885, filed December 7, 1920. This application filed March 21, 1921. Serial No. 454,285.

To all whom it may concern:

Be it known that I, SAMUEL W. RUSHMORE, a citizen of the United States, and resident of Plainfield, in the county of Union 5 and State of New Jersey, have invented certain new and useful Improvements in Cooling Systems, of which the following is a specification.

My present invention relates to one of the 10 simplest and more typical forms of the apparatus described in my prior application, Serial No. 428,885, filed Dec. 7, 1920, the form selected for this application being the internal combustion engine which has the 15 cooling system designed and arranged so that the cooling cycle must operate by water boiling and steam condensing.

As has long been known, cooling by the 20 boiling and condensing cycle has great theoretical possibilities in the way of efficiency and economy of operation of internal combustion engines, but heretofore the practical difficulties in the way of applying it to automobiles have proved insuperable. Al- 25 though much has been said and many patents have been granted in this line, none of them seem to recognize, much less afford solution for the difficulties involved and of the hundreds of makes of automobiles and 30 trucks now in use and on the market, there is not one wherein any attempt is made to utilize boiling and condensing for the cooling cycle. In all of them the radiator is used as a water cooler and not as a steam 35 condenser, everything being designed so that steam evolution can never occur except by accident, and when it does occur, it requires speedy correction in order to prevent serious damage to the motor.

With ordinary water-cooling, however, it 40 is very difficult to design or control the system so that the water will always circulate at the high temperature necessary for efficiency, and many expedients have been de- 45 vised with a view to cooling the water fast enough at high speeds and slow enough at ordinary speeds so as to keep the temperature approximately constant and high at all speeds, without boiling at any speed.

These expedients include thermostatically 50 controlled valves for the water circulation and shutters for the air circulation, but such devices are expensive, cumbersome and liable to derangement. They have the fur- 55 ther disadvantage that in order to afford a

proper margin of safety against boiling the water, they must be adjusted for temperatures many degrees below the boiling point, often as low as 150° to 160° F.

Thermostatic valves for the water circula- 60 tion have been found particularly dangerous when starting with a cold motor in freezing weather, because they normally cut off circulation in the radiator, and the automobile must travel several miles before the cylinders and jacket water become hot enough to 65 operate the thermostat and open the valve. In the meantime, water in the radiator being isolated, small in quantity and very much exposed, will freeze and burst the radiator in a very few minutes, even when the atmosphere is at only a few degrees below 70 freezing. The losses from this cause have been so great, that manufacturers of automobiles using thermostatically controlled 75 throttles warn their customers to cut out the throttle valve and operate the cooling system in the ordinary way during freezing weather, the very time when automatic temperature control is most needed. 80

The difficulty of combining in one apparatus the qualities necessary to make it cool the water slowly enough for starting, slow speeds and cold weather, and yet fast enough for high speeds, heavy loads and hot 85 weather, attends also the water-boiling, steam-condensing method, but the difficulties and causes of failure are different; and they vary with the methods employed to bring about the steaming and condensing. 90

One way which has been proposed involves simply draining off most of the water in the ordinary automobile cooling system so that when the jacket is filled, the water level in the radiator is below the honeycomb. 95 One such proposal entirely overlooks the necessity for automatic means to variably regulate the amount of water pumped back to the water jacket, in such a way as to maintain constant level therein throughout all 100 the wide variations in boiling rates for different engine speeds and loads. A feed pump driven by the engine at proportional speeds will not take care of the extremes of boiling rate variation; and unless there 105 is additional automatic regulation, the water will sometimes overflow into the top of the radiator and be chilled in the usual way characteristic of water cooling, or, at other times, will boil away leaving the hottest 110

part of the water jacket empty. In general, the chilling will occur when engine heat is least, and the boiling off when it is greatest, thereby magnifying temperature variations 5 and the evils thereof instead of rendering the temperature more constant.

Others have proposed to meet this difficulty by the well known expedients, one by pumping a surplus of water in excess of the 10 maximum demands of the motor and maintaining constant level by an overflow outlet at the desired level in the water jacket, returning the excess to the intake of the water jacket; and another by the other well known 15 expedient of submerging the entire water circuit so that the so-called thermo-syphon circulation will be set up.

Both of these schemes, however, seem to have followed the analogy of present auto- 20 mobile water-cooling practice, which is to discharge the cooling medium into the top of the radiator, but where steam thus replaces water as the fluid to be cooled, the radiator becomes a down-flow condenser 25 and there results a series of unexpected difficulties.

The radiator normally contains air, which is approximately 60% heavier than steam at 112° F., and when the steam comes in at 30 the top, it traps the heavy air below it in the honeycomb, and escape of the trapped air is then further prevented by the continuous downflow of the steam and condensate. In this situation, any overflow 35 tube or other low resistance vent at the top of the radiator, would let the steam escape without being condensed and without scavenging out the air. Hence a heavy safety valve must be employed to run up 40 a high internal pressure so that the steam can push the air down far enough to expose the amount of honeycomb surface necessary for condensing the steam. The presence of the air in the condenser greatly decreases 45 its efficiency and the high internal pressures make it dangerous to open the radiator for inspection or refilling while hot, and are otherwise highly undesirable for use on an automobile or truck. In most cases they 50 will make it desirable to have the ordinary standard equipment radiator replaced by heavy expensive piping and boiler-like construction, such as is commonly employed wherever steam is used under pressure.

55 On the other hand, if such down flow condensers are made of sufficient radiating capacity to condense all the steam generated at high speeds and in hot weather, they will chill the condensate too much at other times, 60 and in winter freezing will result.

This is because the down-flow system requires the fluids to travel the full distance from the top to the bottom of the condenser tubes and the less steam there is, the higher 65 up it will condense and the greater will be

the length of chilling tube that the condensate has to traverse.

There is a similar objection to the use of a spacious condensing chamber which is big enough and open enough to permit the 70 steam to balloon freely to the top of the condensing chamber without being condensed on the way up. In such case the entire condenser is brought into play regardless of the amount of steam to be condensed, 75 the result being that the less steam there is, the colder it will get.

By my invention I get constant high temperatures, the lowest of which are near boiling and hence very much higher than the 80 highest attainable by water cooling. These temperatures I may increase up to 220° F. or 230° F. or above, by merely constricting the conduit from the water jacket to the radiator, and I may maintain approxima- 85 tions of these temperatures even when the boiling point of the liquid is considerably lowered as by high altitudes or by the addition of alcohol to prevent the water from freezing in cold weather. The latter is im- 90 portant because in ordinary systems the alcohol lowers the boiling point to between 167° and 176° F., according to the percentage of alcohol. In my system there is practically no loss of the water, or of the 95 alcohol, if alcohol is used. Even without alcohol the honeycomb will not freeze, as will be explained below.

So far as concerns quick warming up and maintenance of high temperatures when 100 idling or in very cold weather, I have all the advantages derivable from the above described by-pass or throttling expedients, but without the necessity of employing them.

Whatever pressures I may have in the 105 water jacket or in the discharge conduit therefrom, there need be no pressure at all in the top of the radiator and even if I use a slight breather valve to prevent too ready breathing of air from the outside into and 110 out of the top of the radiator, the slight pressures which are sustainable thereby when great quantities of steam are being evolved, will disappear as soon as the engine is slowed down and before the operator 115 will be able to reach and open the radiator for inspection or refilling.

Part of the above advantages are the indirect and unexpected results from the qualities which happen to become available 120 merely by selecting for my condenser, any ordinary type of automobile radiator. These radiators, though designed for the entirely different purpose of down-flow water-cooling and to be used in such a way that they 125 are wholly inoperative for condensing purposes in case the water does steam, nevertheless, they happen to have the large radiating capacities and the high radiating rates, as well as the structure, proportions, 130

relative arrangement of parts, and constriction of the up-and-down passages in the honeycomb, which my experiments and discoveries have shown to be suitable for 5 the entirely new method of functioning contemplated by my present invention.

The new functioning, some features of which have been described above, can be brought about by the simple expedient of 10 connecting the water jacket discharge pipe as well as its supply pipe, through the empty space in the bottom of such a radiator.

Referring again to the qualities of the ordinary radiator when thus connected, it 15 will be noted that the water circulating in the bottom of the radiator cannot possibly be adequately cooled except by boiling and, as I have discovered, boiling below the honeycomb will have the effect of ejecting 20 any surplus water at the top thereof because the up and down passages in the honeycomb are very thin, constricted say $\frac{3}{2}$ inch by say $3\frac{1}{2}$ inches, and boiling necessarily results in a blow-off of any solid water contained in 25 the tubes. The same thing happens where the tubes are cylindrical, because they are very numerous, small and closely set.

It will be noted also that the honeycomb 30 is of relatively great superficial area so that different parts of it may easily be at widely different temperatures according to their proximities to the supply of steam and to the action of the cooling fan. At the same time the thickness of the honeycomb from 35 front to rear is short, usually about 4 inches. Hence while different passages may be at widely different temperatures, and while the upper end of the same passage may be cold when the bottom is hot, any given cross section of a passage will have its front portion 40 which is most directly exposed to the incoming draft, substantially warmed by the closely adjacent rear portion.

The front of the honeycomb being some- 45 what cooler than the rear tends to establish a certain amount of short, rear-to-front circulation of steam, the down-flowing condensate being necessarily in intimate heating relation with the upflowing steam so that 50 it reaches the bottom of the honeycomb at steaming temperature.

The aggregate cross sectional area of all 55 the passages for upflow of steam in the honeycomb is small as compared with the height, and though varying somewhat with the make and power of the automobile, it is, for instance, something like 7 square inches for a 6 cylinder 25 horse power engine, while the amount of steam that must find escape 60 through this area, split up, as it is, into such a multiplicity of passages, is always great enough to maintain a swift steady flow of the steam pressing straight on upward while being continuously diminished by condensation, until it is all condensed. Hence it re-

sults that the steam sweeps the air upward out of all the active parts of the honeycomb and toward the low resistance outlet at the top; while, on the other hand, the steam cannot deposit water except in said active parts 70 of the honeycomb whence the entire path of down-flow of condensate is through said active parts which are being kept at boiling point by the continuous upflow of steam.

Increased volume of steam due to increase 75 of load upon the motor, or decreased cooling efficiency of the air, as in hot weather, may result in raising or lowering the height of the circulation, but without changing the intimacy between the upflow of steam and the 80 downflow of condensate.

The front-to-rear thinness of the honeycomb, its small base area for entry of steam as compared with its height, and the multiplicity, smallness, and close setting of tubes 85 or passages, all contribute to make definite and dependable the above described automatic increase and decrease of the height of the circulation in the honeycomb and the exact automatic regulation of the actively 90 operating condenser area, so that the condensate is returned at boiling temperature regardless of how little or how much steam is being generated.

The honeycomb will not freeze up when 95 connected and operated in accordance with my invention. This is because the honeycomb is normally dry; it is wetted only by condensed steam penetrating upward from below; the passages are so constructed that 100 they will not be wet any higher up than the points that are kept warm by steam condensation and of course not as high as the further points that are kept above freezing by conduction in the metal walls; wetted areas 105 are constantly drained by gravity; and as soon as the steam recedes they are dried by the heat reabsorbed from the adjacent metal. Since the wetted area recedes downward when the steam recedes, there will be no 110 water to freeze in the parts of the radiator where freezing temperatures exist.

The latent heat absorbed in changing water to steam is so great that the amount of water which it is necessary to pass 115 through the water jacket is very much less than in systems where cooling is done entirely by water, which, in the well regulated thermostically controlled systems, is usually only about 150° to 160° F. Theoretically cooling by the steam method on an automobile running "ten miles to the gallon" of gasolene, or say four gallons per hour, at 40 miles per hour, requires only 120 six or eight gallons of water per hour to be boiled and recondensed. A much greater supply of water, however, can do no harm, because it enters the jacket hot, that is near 212°. Hence, while my system may be specially designed for circulating only a 130

safe margin of surplus water, say ten to twenty gallons of water per hour, thereby utilizing a smaller pump and much less power, there is nothing to prevent applying it to ordinary systems equipped with pumps of much greater capacity. This makes it applicable to automobiles in which the water jacket spaces in the motor are so formed that high speed circulation of excess water 10 is necessary to keep them swept clear of steam and trapped air. It is therefore an advantage of my system that its success does not depend on limiting the speed of circulation of the water.

15 In my earlier experiments, which have since resulted in successfully applying my above method to standard automobile equipment, I encountered two difficulties. The first is that although my present method requires circulation of only a small amount of water, this water when changed to steam increases in volume over seventeen hundred times with the result that friction in the return conduit from the water jacket 20 to the radiator may be considerable and may cause back pressure on the water jacket. I have discovered, however, that when desired, this can be gotten rid of by using a sufficiently large conduit at this point.

25 Preferably, however, it is turned to advantage by using a constricted conduit, and varying the constriction to get any desired back pressure on the water jacket. This expedient makes it easily possible to raise 30 the boiling point in the water jacket to 220° F. or 230° F., or above, where water alone is used, and it is of particular advantage where alcohol and water mixtures are used, because thereby the boiling point 35 of the mixture, which may be say 167° to 176° F., can be raised to the desired extent. This necessitates the use of a positively acting pump, the pressure on the up-side of the water circuit being abnormally increased by the back pressure of steam in 40 the discharge. Furthermore, the water drawn from the bottom of the radiator being at boiling point must go to the intake of the pump by gravity, because applying 45 suction to draw it up will only result in permitting evolution of steam to satisfy the suction, without lifting the water.

50 For all of these reasons, the intake of the pump should be at or below the normal level 55 of water in the radiator, and the pump should be a force pump adapted to positively force the water into the water jacket against gravity, and against any back pressure of steam that can exist even under 60 the worst conditions.

65 It will be noted that while the honeycomb as a whole is in one sense in shunt relation to the low resistance path of the water through the bottom of the radiator, it also has the relation of a vent or open

70 conduit in series between the steaming section of the circulation and the outer atmosphere, but of such a nature that in normal operation the steam cannot get out because it is condensed before it gets far enough. Hence it operates in effect like a massless, 75 pressureless safety valve to prevent all escape of steam to the atmosphere except under very abnormal conditions when it is highly desirable that such escape be permitted.

80 The above and other features of my force-feed circuit for water and steam, combined with the variable height circulation in a honeycomb below which force-feed circuit releases steam, may all be more fully understood from the following description and the accompanying drawings, in which:—

85 Figure 1 is a side elevation conventionally indicating the usual elements of a water cooling system as commonly employed on automobiles, etc., but arranged so as to embody one form of my invention;

90 Fig. 2 is a vertical section on the line 2—2, Fig. 1, in which the construction is diagrammatically indicated;

95 Fig. 3 is a similar view on the line 3—3, Fig. 2;

Fig. 4 is a true size detail section on the line 4—4, Fig. 2;

95 Fig. 5 is a detail showing another illustrative form of air cooled radiator which may be employed;

100 Fig. 6 is a detail section showing a valved vent.

105 Fig. 1 shows the usual crank case 1 and cylinder block 2 of a four cylinder motor of the automobile type, the upper parts of which are inclosed by water jacket 3. The water cooling system is conventionally indicated as including the radiator 4 preferably located on the same level with the motor and directly in front of it, so that the lower part of the radiator is below the level of the water-jacket of the motor. The circulation of the water from the bottom of the 110 radiator, is through a conduit comprising outlet 5, flexible coupling 6, and pipe 8 to pump 9, the latter being preferably driven by the engine at directly proportioned 115 speeds. The pump is indicated as being a "gear pump" but this is only to illustrate the pump which may be of any known or desired construction, adapted to receive boiling water and force it into and through the 120 water jacket against friction and any back pressure that may be caused by steaming. The pump discharges through a conduit including pipe 10, branches 15, 16, water jackets 3, outlet pipe 17, 18 and a single return 125 pipe 19. The pipe 10 may contain a check valve 7 to insure against back flow of water or steam, as might otherwise happen under certain conditions, as for instance, when the engine and pump stop.

The return pipe 19 is connected to the cavity below the honeycomb in the radiator, as by flexible joint 23 and downward pipe 24 which, if desired, may be recurved as at 5 25 so as to enter the radiator through the bottom, instead of through the side.

As shown in Fig. 2 the inlet pipe 25 may be provided with a horizontally directed discharge nozzle 26 adapted to discharge the 10 incoming hot water straight across in the direction of the exit through pipe 5, but this is not necessary.

The important point is to afford the incoming hot water a relatively low resistance, 15 low pressure path in the bottom of the radiator, to the outlet 5. All of the desirable relations may be attained by arranging the discharge path through the usual horizontal cavity, beneath the "honeycomb" section 20 which is the main, effective radiating element of the structure. Thus arranged the bottom of the radiator constitutes an effective steam separator operating to facilitate evolution and escape of steam from the 25 incoming hot water.

The honeycomb is conventionally indicated as comprising thin sheet metal walls affording fore and aft passages *a*, *a* for the air draft which are usually about 4 inches 30 through, by about $\frac{1}{4}$ inch diameter; also interior vertical passages *b*, *b* for vertical circulation of the hot fluid in intimate contact with the large air radiating surfaces constituting the air passages. In the type 35 here indicated these vertical passages are usually about $\frac{3}{2}$ inch by $3\frac{1}{2}$ inches to 4 inches in horizontal cross section and the number of them may be sufficient to afford an aggregate flow section of about 7 square 40 inches. In other types of honeycomb there are cross passages as at *c*, *c* Fig. 5, affording opportunity for cross circulation. In this form the vertical passages are not straight, but the cross tubes are so many, so small, and 45 so closely set that the functioning is not materially different so far as concerns the desirable features heretofore described as attainable by the use of any of these well known types of automobile radiators.

50 Where the honeycomb is of the type comprising a multiplicity of upright cylindrical tubes held in cross-members that serve as cooling ribs or fins, the desired limited-height, up-and-down flow in individual tubes 55 will occur, though the tubes be not more than $\frac{1}{4}$ inch in diameter.

With any of these arrangements, it is obvious that while the water is cool it will be pumped around and around through the 60 circulating system and across from inlet nozzle 26 through the low resistance path to outlet pipe 5, until the incoming water begins to liberate steam, which will rise and set up the circulation in the honeycomb.

65 Even if the radiator has been filled to or

above the honeycomb, it is not likely to remain full very long because I prefer to employ an overflow pipe 20, or other suitable connection with the outer air, whereby the interior of the radiator is kept at or near 70 atmospheric pressure. Hence the incoming water will become actively boiling, and the conditions are such that this operates to force any surplus water or air upward and out through the overflow pipe 20. 75

The water in the radiator being at or below the bottom of the honeycomb, either by original filling or by automatic ejection of surplus, if over filled, the functioning of the device at the various speeds from idling 80 speeds or cold weather conditions and through the intermediate variations up to and including the highest speeds and heaviest loads in the hottest weather, will be, according to the methods heretofore described. 85

In the drawings the pump is shown as having its intake at or below the lowest level of the water in the bottom of the radiator so that under normal conditions when the water is at boiling point and will 90 not respond to suction, the intake will be supplied by gravity flow. The showing of the pump is indicated as diagrammatic, but it will be understood that it must be sufficiently positive so that at low speeds and 95 under all conditions it will be able to force the required amount of water through the water jacket against friction and any back pressure that may be set up by steam evolution. 100

The back pressure on the water jacket will depend on the size of the pipe leading from the top of the water jacket to the bottom of the radiator, or, more strictly speaking, upon the total resistance which 105 this conduit offers to the passage of the steam. A throttle valve to vary the constriction of this conduit may be of advantage, particularly for aeroplanes, since a proper constriction will keep up the boiling point in the water jacket independently of the altitude of flight. Such throttle may have automatic control, either pressure or 110 thermostatic, without danger of freezing the radiator. 115

While the specific purpose which I have had in view has been the embodiment of above steam cooling methods, in the present day constructions of automobiles, trucks and the like without materially changing 120 the structure of the radiators which are designed for down flow of the hot water, nor their proportions, nor their location in front of the engine with the lower collecting cavity considerably below the level of the water jacket, and while there is special advantage in my discovery that now standard apparatus can be utilized for my purpose with only slight changes involving no additional parts and practically no expense, it will be 130

evident that in any new apparatus especially adapted for the practice of my invention, various changes may be made; also that various features contributing to the 5 success of my invention may be employed either together or separately for analogous purposes, in other apparatus, as for instance in airplanes, and stationary plants.

For instance, the vent to atmosphere at 10 the top of the radiator may have its resistance very substantially increased by a safety valve, thereby increasing its condensing capacity, without endangering any of the well built radiators of standard types; and by 15 employing special constructions, the pressure may be raised to any desired extent; and of course heavier more substantial constructions may be specially desired.

While the space in the bottom of an ordinary radiator will hold all the water 20 really needed, a greater supply may be provided for by laterally enlarging the radiator at this point, and obviously the filler cap may be located much lower down, near 25 the normal level of the water.

In the form shown in the drawings there 30 is a small cock located at approximately the desired water level, through which the water may be drawn down to said level. This should of course be done while the 35 pipes and water jacket are kept full by running of the motor.

As the capacity of the ordinary honeycomb is more than sufficient to condense all 35 the steam that can be formed in the operation of the engine for which the radiator is designed, it is quite possible to cheapen construction by decreasing the size of the honeycomb, in which case the space saved may 40 be utilized for containing a larger supply of water.

The term "honeycomb" herein is used in a rather broad sense to indicate the main active heat-dissipating elements of the radiator, the important features of which, so far as concerns my present invention, are the upflow paths for the steam adapted for 45 down drainage of water; the small aggregate flow-section of the paths as compared with their height; and the open tops for 50 the paths whereby air forced up from below by the steam may escape into a common cavity or to the open air.

These and other features whereby the flow 55 of steam is steadily and rapidly upward even when the steam production is smallest, and whereby variations in the amounts of steam are taken care of merely by varying the height to which the steam penetrates, 60 may be embodied in many different condenser constructions which have not the appearance of a "honeycomb" and which I call a honeycomb merely for convenience.

In Fig. 6 I have shown a valve construction that may be substituted for the ordi-

nary filler cap, to serve as the low resistance vent to the atmosphere in place of the overflow pipe 20, the latter being then plugged or omitted. The part 21^a is provided with a spring closed valve 29 closing outlets 31. 70 This valve may be designed or adjusted so as to be a mere breather opening under slight pressure, or its opening resistance may be increased to any desired extent. If adjusted to open under the pressure of say 5 75 lbs. per square inch, the maximum capacity of the condenser will be greatly increased. If desired, a similar but oppositely directed valve 30 may control inlet passages 32, whereby air may be admitted and vacuum 80 prevented or relieved. These valves may be protected by closure cap 27 having normally open vents 28.

I claim:

1. In a motor vehicle of the general type 85 characterized by an internal combustion engine of widely variable speed and heating capacity and water-jacketed for cooling purposes; an air cooled radiator located in front of one end of the motor, comprising an intermediate portion of great heat radiating capacity affording a multiplicity of transverse paths for through flow of the cooling air, and interior, up-and-down paths for up-flow of steam and drainage of water by 90 gravity, a lower portion of small heat radiating capacity affording a collecting cavity into which said paths drain and in which the water level is maintained below the level in the water jacket, and an upper cavity to 95 which all said paths are open for escape of air; and a conduit with force pumping means leading from the lower collecting space in the radiator to the water jacket; and, in combination with the said elements 100 of such a vehicle, means for operating said pumping means at a rate sufficient to oversupply the water-jacket, and a single continuous return conduit for the surplus water and steam leading from the upper part of 105 the water jacket discharging into said lower collecting space in the radiator, thereby causing separation of the surplus water and steam in the lower part of the radiator and continuous flow of steam upward into said 110 upward paths, forcing air or other excess fluids above it into the upper cavity in the radiator.

2. In a system for cooling an internal combustion engine by the boiling and condensing cycle, an internal combustion engine jacketed for application of the cooling liquid, a radiator comprising a condenser portion of large radiating capacity having a flow path which is of small flow section as compared with its length and which is open at both ends for in and out flow of fluids, a container of low radiating capacity closing 115 in one end only of said flow path and into which the latter drains, in combination with 120

- a force pump and circuit for forcing fluid serially through the jacket and said container at rates sufficient to over-supply the water jacket, and connecting with said condenser only through said container the parts being proportioned and arranged to maintain the level of the liquid in the container below the level of the adjacent end of the flow path through the condenser.
3. A cooling system for water-jacketed internal combustion engines, said system comprising in part, a force pump circuit for continuously circulating an over-supply of cooling fluid which is of small radiating capacity; and in part, upwardly extending tubes each open at the upper as well as the lower end and constituting a condenser of great radiating capacity, and which is located above an exposed portion of said circuit wherein the steam is separated from the surplus circulating water and whereby steam separated from the water can flow directly into the lower ends of said tubes; the air forced out by the rising steam can escape from the upper ends of the tubes; and the water of condensation can flow by gravity directly from the same tubes to the water circulating system.
4. In a cooling system for internal combustion engines, a force feed water circulating system of small heat radiating capacity serially including a water jacket, a water outlet pipe from said jacket, and a water container to which said pipe is connected, in combination with large capacity radiating means above the water container, interposed between it and a low resistance outlet for escape to the outer air for steam, air or water.
5. In a cooling system for internal combustion engines, a force feed water circulating system of small heat radiating capacity serially including a water jacket, a water outlet pipe from said jacket, and a water container to which said pipe is connected, in combination with large capacity radiating means above the water container, interposed between it and a low resistance outlet for escape to the outer air for steam, air or water, the flow section for the steam being relatively small as compared with the total condensing capacity so that the steam will penetrate the condenser only to a distance proportional to the amount of the steam.
6. In a system for cooling an internal combustion engine by the boiling and condensing method, an internal combustion engine jacketed for application of the cooling liquid, a radiator comprising a condenser portion of condensing capacity equal to the maximum requirements of the engine but of relatively small flow section for the purpose described and a water container communicating with one end only of the flow path and into which the latter drains, in combination with a force pump circuit through the jacket and said container of small radiating capacity operating to over-supply the water jacket and to maintain the level of the liquid in the container below the level of the adjacent end of the flow path through the condenser.
7. In a system for cooling an internal combustion engine by a boiling and condensing cycle, an internal combustion engine jacketed for the application of the cooling liquid, a radiator comprising a condensing portion having a flow path which is of small cross-section as compared with its length, and which is open at both ends for in and out flow of liquids, a container adapted to serve as a steam separator communicating with one end only of said flow path and into which the latter drains, in combination with a force pump and circuit for forcing all the circulating fluids serially through the engine jacket and said container at rates sufficient to over-supply said jacket; the part of said circuit which leads from the water jacket to the container being constricted to afford desired resistance and resulting back pressure in the water jacket.
8. In a system for cooling an internal combustion engine by the boiling and condensing method, an internal combustion engine jacketed for application of the cooling liquid, a radiator comprising a condenser portion of condensing capacity equal to the maximum requirements of the engine but of relatively small flow section for the purpose described, and a water container of relatively small radiating capacity communicating with one end only of the flow path and into which container the flow path drains, in combination with a force pump and circuit for forcing water serially from the container through the jacket and the resulting water and steam into said container, at rates sufficient to over-supply the water jacket; the parts being proportioned and arranged to maintain the level of the liquid in the container below the level in the water jacket.
9. In a system for cooling an internal combustion engine by the boiling and condensing cycle, an internal combustion engine jacketed for application of the cooling liquid, a radiator comprising a condenser portion of large radiating capacity having a flow path which is of small flow section as compared with its length and which is open at both ends for in and out flow of liquids, a container of small radiating capacity communicating with one end only of said flow path and into which the latter drains, in combination with a force pump and circuit for forcing water serially from the container through the jacket and the resulting water and steam into said container, at rates sufficient to over-supply the water jacket; the parts being proportioned and arranged to maintain the level of the liquid

in the container below the level in the water jacket.

10. In a motor vehicle of the general type characterized by an internal combustion engine of widely variable speed and heating capacity and water-jacketed for cooling purposes; an air cooled radiator comprising an intermediate portion of great heat radiating capacity, relatively thin from front 10 to rear, affording a multiplicity of transverse paths for through flow of cooling air, and interior, up and down paths of small flow section for upflow of steam and return drainage of water by gravity, a lower portion 15 of heat radiating capacity much less than the average heat generating capacity of the engine, affording a collecting cavity into which said paths drain and in which the water level is lowered below the level 20 in the water jacket, and said radiator having also an upper cavity to which all said paths are open for escape of air; and, in combination with said elements of such a

vehicle, a conduit leading from the lower collecting space in the radiator to the water 25 jacket; a positively acting pump for said conduit having its intake supplied by gravity from said collecting space, adapted to fully supply the water jacket with water at all 30 speeds and when the water is boiling regardless of the variations of heat and back pressure in the water jacket; a return conduit from the upper part of the water jacket discharging into said lower collecting space in the radiator; thereby facilitating evolution 35 of steam and discharge thereof in the lower part of the radiator and continuous flow of steam upward into said upward paths, forcing air or other excess fluids above it into the upper cavity in the radiator.

Signed at New York, in the county of New York, and State of New York, this 19th day of March, A. D. 1921.

SAMUEL W. RUSHMORE.
